UNITED STATES PATENT OFFICE.

JAMES A. FLINT, OF WASHINGTON, DISTRICT OF COLUMBIA, ASSIGNOR TO THE GOVERNMENT OF THE UNITED STATES.

TORPEDO.

Application filed November 18, 1919. Serial No. 338,952.

To all whom it may concern:

Be it known that I, JAMES A. FLINT, a citizen of the United States, residing at Washington, District of Columbia, have invented new and useful Improvements in Torpedoes, of which the following is a specification.

This invention relates to improvements in torpedoes and more particularly to the pistols associated with the combustion flask.

It is well-known to those familiar with the art that the modern automobile torpedo used in the Navy is driven by high temperature high pressure gases composed primarily of compressed air, steam and the products of combustion of the heating medium for converting the water into steam in the combustion flask. This heating medium now generally employed is sprayed alcohol which is ignited on launching the torpedo by the flash from the mechanism technically known as the pistol. It sometimes happens that the pistol does not ignite the alcohol which results in what is known as a "cold run", giving the torpedo a slower speed, a shorter range and consequent inaccuracy.

It is one of the objects of the present invention to prevent cold runs as much as possible by providing a plurality of pistols adapted to insure the proper ignition of the alcohol spray.

A further object is to provide a simple and practical arrangement of the pistols whereby they will be fired successively into the combustion flask to positively insure the ignition of the spray.

A further object is to provide a reliable and efficient firing mechanism which may be compactly arranged and inexpensively manufactured and assembled.

Other objects will be in part obvious from the annexed drawings and in part indicated in connection therewith by the following analysis of this invention.

This invention accordingly consists in the steps of the process and their relation to each other and in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and

relation contemplated by this invention, drawings depicting a preferred form have been annexed as a part of this disclosure and in such drawings, like characters of reference denote corresponding parts throughout all the views, of which:

Figure 1 is a side elevation of a portion of the combustion flask and pistols applied thereto.

Figure 2 is an end view of the part shown in Figure 1.

Figure 3 is a longitudinal sectional view of one of the pistols shown in Figure 1.

Referring now to the drawings in detail and more particularly to Figure 1, 5 denotes the combustion flask provided with a head 6 into which are screwed two pistols 7 and 8. These pistols comprise a body member as indicated at 10 in Figure 3 and a trigger mechanism in a portion 11 positioned at an angle thereto.

In Figure 3 the pistol 7 is shown which is substantially the same as the pistol 8 and it will be sufficient to describe but one of these in order to fully understand the invention.

The threaded end 12, Figure 3, is connected in any suitable manner by coupling 13 and pipe 14 with a source of compressed air. Within the portion 11 is a piston or plunger 15 provided with a stem 16 and coil spring 17 seated in a recess 18. The part

10 is provided with an end block 20 to permit ease of assembling while the opposite end 21 is adapted to be screwed into the head 6 of the combustion flask. Within the part 10 there is a plunger 22 provided with a firing pin 23 adapted to engage a cap or cartridge placed in recess 24. This plunger or piston 22 is drawn back to com-

press a coil spring 25 and is held in firing position by means of a latch 26 engaging a hook or flanged end 27 of the pin 22. The latch is held in position by means of a

spring 28 in substantial alignment with the member 16 of the piston 15. When air is admitted through the pipe 14 the plunger 15 will be depressed against the action of the spring 17 allowing the end 16 to engage the part 30 of the trigger 26 thereby to release the hook end and permit the plunger

22 to move relatively towards the left to fire the cartridge.

In the side wall of the chamber containing the piston 15 is an opening 31 commu-

nating with a pipe 32 leading to the pistol 7. As the pistols 7 and 8 are substantially duplicates, it will be seen that after the pistol 8 has been fired the air will escape through this passage 32 to actuate the pistol 7 which fires immediately thereafter. This double firing of the pistols is almost certain to ignite the alcohol spray within the combustion flask and accomplish the desired result thereby greatly increasing the range of the torpedo and reducing the chances of a cold run to a minimum.

It is thus seen that the present invention provides a simple and practical arrangement of pistols particularly adapted for use in automobile torpedoes and adapted to accomplish among others all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency of the following claims.

What I claim is:—

1. In a torpedo, in combination, a combustion flask, a pair of pistols mounted in the head thereof, a source of compressed air connected with one pistol, and a pipe connecting said first mentioned pistol with the second pistol whereby after the first pistol is fired the second pistol will be fired.

2. In a torpedo, in combination, a combustion flask, a pair of pistols mounted in the head thereof, a source of compressed air connected with one pistol, and a pipe connecting said first mentioned pistol with the second pistol whereby after the first pistol is fired the second pistol will be fired, by uncovering a port and allowing the air to flow into the second pistol.

3. A double pistol for torpedoes each comprising a casing member having a firing pin, a trigger, and an air actuated plunger adapted to actuate said trigger, one of said casing members having a vent at one side adapted to be connected with the second pistol whereby the air after actuating said plunger, will pass through said vent to actuate the second pistol.

Signed at Washington, District of Columbia, this 11th day of July, 1919.

JAMES A. FLINT.
